UNITED STATES PATENT OFFICE.

DÉSIRÉ LÉON BOUMAL, OF NEW YORK, N. Y.

HORSESHOE.

SPECIFICATION forming part of Letters Patent No. 697,791, dated April 15, 1902.

Application filed October 12, 1901. Serial No. 78,417. (No model.)

To all whom it may concern:

Be it known that I, DÉSIRÉ LÉON BOUMAL, a citizen of Belgium, residing at New York, in the county of New York and State of New York, have invented certain new and useful Improvements in Horseshoes, of which the following is a full and complete specification, such as will enable those skilled in the art to which it appertains to make and use the same.

The object of this invention is to provide improved means for shoeing a horse or for connecting a shoe with the foot of a horse, a further object being to provide means whereby a shoe may be connected with a diseased hoof without driving nails into the hoof, whereby a hoof which is diseased or afflicted in any way may be protected until a cure is effected, and a further object being to provide improved means for securing a shoe to the foot of a horse, whereby a man may shoe his own horse without the necessity of going to a blacksmith; and with these and other objects in view the invention consists in a device or appliance of the class specified constructed as hereinafter described and claimed.

In the drawings forming part of this specification, in which the separate parts of my improvement are designated by the same reference characters in each of the views, Figure 1 is a side view of my improved horse-shoeing appliance and showing a shoe connected therewith; Fig. 2, a back view thereof, and Fig. 3 a perspective view of the horse-shoeing appliance with the shoe removed.

In the practice of my invention I provide a device of the class specified comprising two similar substantially segmental portions *a*, which are hinged together at *b*, the point of connection at *b* being at the central front portion of the hoof when the device is applied thereto. The separate parts *a* of this device are designed to inclose the hoof and are preferably higher at the front than at the back and are also preferably of a height about equal to the height of the average hoof, and said parts *a* are preferably composed of sheet metal and are provided at the back portion thereof with backwardly-directed jaws *c* and *c'*, which are arranged in pairs and which are designed to be connected by bolts *d*, having nuts *d'*.

The inner parts of the jaws *c* are prefer-

ably slightly curved inwardly, as shown at *c*³, so as to make the device more closely fit the hoof, and secured to and within the bottom portions of the separate parts *a* of the device are segmental pieces or inwardly-directed flanges *e*, composed of metal or any other suitable material and which are preferably from one-quarter to one-half of an inch thick, and these pieces *e* may be secured in position by rivets or screws, as shown at *g*, and one of said pieces is provided at its end with flat dowel-pins *h*, which enter corresponding recesses in the ends of the other piece, which are shown in dotted lines at *h*².

In practice the device, as shown in Fig. 3, is secured to the hoof of the horse by means of bolts *d*, and a shoe *k* is then secured to the bottom thereof by means of screws *k*², any desired number of which may be employed, said screws passing into the segmental pieces *e* at *k*³. By means of this construction a shoe may be securely connected with the hoof of a horse without driving nails into the hoof, and the hoof will be protected, if such protection is necessary, and any one may quickly and easily shoe his own horse.

Although I have described the parts *a* as composed of sheet metal and the parts *e* as composed also of metal and secured thereto, it will be apparent that these parts may all consist of castings, in which case the parts *e* will be provided with holes *k*³, as indicated in Fig. 3, to receive the screws *k*², the shoe being also provided with holes, through which the screws are passed.

Having fully described my invention, what I claim as new, and desire to secure by Letters Patent, is—

A device of the class described comprising two members *a* hinged together at *b*, said device being adapted to be secured to and to inclose the hoof of a horse, the connection with the hoof being such that the point where the separate members *a* are hinged together is, when the device is connected with the hoof, at the central front portion of said hoof, said members being also provided at their rear ends with projecting jaws by which they are secured to the hoof, said jaws being arranged in pairs and the bottom pair being set inwardly farther than the upper pair, and said separate members being also provided at the

bottom thereof with inwardly-directed flanges or supports to which a shoe may be secured, one of the members being also provided at each end with a projection adapted to enter 5 a corresponding socket or recess in the ends of the other member, substantially as shown and described.

In testimony that I claim the foregoing as

my invention I have signed my name, in presence of the subscribing witnesses, this 11th day of October, 1901.

DÉSIRÉ LÉON BOUMAL.
